UNITED STATES PATENT OFFICE.

JOSEPH A. ROSTRON, OF BOSTON, MASSACHUSETTS.

ELECTROMAGNETIC APPARATUS.

Application filed May 3, 1920. Serial No. 378,476.

To all whom it may concern:

Be it known that I, JOSEPH A. ROSTRON, a citizen of Great Britain, residing at Boston, in the county of Suffolk and State of Massachusetts, have invented certain new and useful Improvements in Electromagnetic Apparatus, of which the following is a specification.

The present invention relates to "buzzers," 10 so called, in the general class of electromagnets and electromagnetic switches, adapted as rapid make and break contact apparatus to produce a vibration making a sound or ringing a bell, and to magnets 15 for other uses.

The object of the invention is to provide improved electromagnetic apparatus of this sort which shall be extremely simple in construction, economical to manufacture, compact, and efficient in operation.

In particular it is an object to avoid the customary U-shape of magnet, which is relatively expensive to construct, and to do this without loss of magnetic efficiency; also to 25 produce an armature of inexpensive but effective type, and to provide also for adjustments.

According to the present invention an inexpensive, straight, flat bar of iron is the core 30 adapted to attract a sheet metal armature. The sides of the end portions of the metal core constitute pole faces for the sides of the end portions of the armature. The coil is wound about the middle of the core. The 35 armature is substantially parallel to the core at a little distance therefrom, but the sides of its end portions are offset toward the core so that the armature constitutes an iron path from one end to the other of the straight 40 core, such path being bowed out around the winding thereon. To obtain a buzzer effect the armature may have a sheet metal integral extension edgewise from its middle, long enough to have necessary flexibility for vibration when clamped at the extremity.

The neck leading to this clamped end may make and break contact with a bit of sheet-metal constituting a stationary switch member just beside it. A very simple and efficient device is thus provided that is procurable for a small fraction of the cost prevailing for similar articles today. The principle may however be applied in more expensive and larger apparatus with corresponding advantages.

In the accompanying drawings illustrating the invention:

Figure 1 is a perspective view of one embodiment of the present invention showing the base in dot-and-dash lines and the armature in contact with the core:

Figure 2 is a section on the line 2—2 of Fig. 1, looking in the direction of the arrows;

Figure 3 shows the same as a bell.

The electro-magnet of the present invention comprises a flat, straight core 2, the sides of whose ends 4 and 6 constitute pole faces being in fact a simple section cut from a length of bar iron and an energizing winding 14 thereon. The armature 8 is preferably a stamping of thin sheet iron, set parallel therewith, the sides of whose end portions 10 and 12 are adapted to contact with the sides of the pole pieces 4 and 6, respectively. The armature ends are offset towards the poles from the body portion of the armature, it being ordinarily less expensive to bend such thin sheet metal, and less expensive to wind the coil on a straight core. In the illustrated embodiment of the invention, the offset ends are thus shown upon the sheet metal armature, the offsetting being effected by a die which blanks out the shape and then bends the ends, which may be all at one operation. The armature is a T-shaped piece, with the leg of the T constituting a flexible stem that holds the armature proper, whose poles are at the ends of the arms of the T. When the winding 14 is energized, the armature will be drawn to the core until their respective ends are in contact, thus closing a good magnetic circuit. As the winding is flat on account of flat shape of the core, the armature body can fairly be close to it and substantially parallel with it, with one side 18 of the coil lying in the bowed space 16 of the armature, whereby a very compact structure is obtained.

In order to adapt the electro-magnet to switch purposes, the armature is made the movable member. The core is accordingly shown as stationary, supported upon the bottom 20 of an insulating base which may be a mere wooden cup with the bar iron core simply pressed in tight; although additional fastening may be employed if desired such as tacks driven into the wood. The extremity of the leg 22 of the T is fastened

to the bottom 24 of a recess 26 in the side wall 28 of the base. The head of the **T** is mounted parallel to the core, so that its ends may be drawn to the poles, the somewhat 5 springy sheet-metal leg 22 of the **T** bending to permit such movement, and flying back immediately on the weakening of the magnet. When the armature occupies its normal open position, it contacts with a sheet- 10 metal switch member 30 which is fastened in the same recess 26, with the leg of the armature, and with the same single screw, being insulated therefrom at 32. Thus a current is passed through the coil of the magnet. 15 When the armature is attracted to the core, it breaks contact with the switch member, thereby opening the magnet circuit. There- upon the armature springs back, away from the magnet. Contact between the armature 20 and the switch member may thus be rapidly made and broken in accordance with rapid energization of the winding 14, to cause the operation of a "buzzer" or similar device in well known manner. Terminals 36 and 38 25 are conveniently made in the wooden wall 28 by screws passing through it. Of course more elaborate contacts and adjustments can be made at will, but it is one advantage of the invention that adjustments can be 30 made in the simple form illustrated by merely bending the short contact piece 30 or the armature leg 22. To use the invention as a bell a hammer 40 may be attached to the armature and a bell 42 mounted on the 35 base, as indicated in Figure 3. The base can be made of any other suitable material if found more desirable than the wood men- tioned.

It is intended that the patent shall cover 40 by suitable expression in the following claims whatever patentable novelty is involved in the invention disclosed.

I claim as my invention:

1. A vibrator comprising, in combination, 45 a casing having fixed within it an electro- magnet and one electrical contact; and an armature, secured in the casing between them and bearing the other electrical contact; the magnet core and said armature 50 being flat metal sheets arranged with their broad surfaces parallel to each other; the said magnet sheet being relatively thick, con- stituting a straight bar and having the wind- ing about its middle; and the said armature 55 sheet being relatively thin, elastic and flexi-

ble, and having its end portion bent around the end portion of the said winding on the magnet, to proximity with the magnet core, for vibrating toward and from the broad side of said core. 60

2. An electric vibrator having, in combi- nation, a section of flat bar iron comprising a core, the sides of whose ends constitute pole faces and about whose middle is wound an energizing coil; and a **T**-shaped elastic 65 sheet iron armature, the arms of the **T** being parallel to said bar, overlying the coil with their ends offset from the plane of the middle part toward the respective pole faces to co-operate closely therewith notwithstanding the coil intervening between the straight armature and core; a base to which the leg of the **T** is secured; and a terminal for make and break contact with the said leg 70 said leg and terminal having contacts for make and break of an electric current. 75

3. In a vibrator, the combination of two flat, broad strips of permeable material ar- ranged with their broad surfaces parallel to each other; one of them being relatively 80 thick and constituting an electro-magnet core, and the other relatively thin and con- stituting its armature; the said core strip being straight and having its energizing coil wound about its middle; and the said arma- 85 ture strip being relatively thin, elastic and flexible, and having its end portion bent around the end portion of the said winding to proximity with the magnet core, for vi- brating toward and from the broad side of 90 said core.

4. A make and break apparatus comprising in combination an electromagnet whose core is of straight bar iron whereon is wound medially an electric coil, the sides of 95 the ends of the bar being exposed; an arma- ture of sheet metal bowed around said coil with the sides of its ends against and par- allel with the said sides of ends of the mag- net; a tongue extension of the sheet metal 100 comprising the armature, perpendicular thereto, supporting it and constituting part of the electrical circuit; and a base to which it is secured at a distance from the arma- ture, thereby to vibrate to and from the 105 side of the bar.

Signed at Boston, Massachusetts, this 15th day of April, 1920.

JOSEPH A. ROSTRON.
